UNITED STATES PATENT OFFICE.

MABEL JOSEPHINE STEARNS, OF NEW YORK, N. Y., ASSIGNOR TO PARKER, STEARNS & COMPANY, OF BROOKLYN, NEW YORK, A CORPORATION OF NEW YORK.

DESIGN FOR A RUBBER BATHING-CAP.

45,658.

Specification for Design.

Patented Apr. 21, 1914.

Application filed December 15, 1911. Serial No. 666,070. Term of patent 7 years.

To all whom it may concern:

Be it known that I, MABEL JOSEPHINE STEARNS, a citizen of the United States, and resident of the borough of Brooklyn, in the city and State of New York, have invented a new, original, and ornamental Design for a Rubber Bathing-Cap, of which the following is a specification, reference being had to the accompanying drawing, forming part thereof.

My new design for a rubber bathing cap is shown in the accompanying drawing, in which—

Figure 1 is a side view, and Fig. 2 is an inverted plan view.

I claim:

The ornamental design for a rubber bathing cup, as shown.

MABEL JOSEPHINE STEARNS.

Witnesses:

F. GEORGE BARRY,
C. S. SUNDGREN.
